UNITED STATES PATENT OFFICE.

LOUIS WIDMAYER, OF NEW BRITAIN, CONNECTICUT, ASSIGNOR TO P. AND F. CORBIN, OF SAME PLACE.

DESIGN FOR LOCK-CASES.

Specification forming part of Design No. 7,076, dated December 23, 1873; application filed December 3, 1873.
[Term of Patent 7 years.]

To all whom it may concern:

Be it known that I, LOUIS WIDMAYER, of New Britain, in the county of Hartford and State of Connecticut, have invented or produced a Design for Lock-Cases, of which the following is a specification:

The accompanying drawing represents the said design.

Near the center of the case is a representation of a locomotive-engine at *a*, with a scalloped frame, *b*, around it. Around the flat portion of the case there are bead-work ornaments *c*, with corner leaf ornaments *d*. The vine, stem, leaves, and flowers *e* are above and below the locomotive design, the whole of the ornaments being in relief. The ogee edge of the lock-case is ornamented with scroll-work and leaflets at *g*, as shown in the draw-

ings. The nosing of the lock is of an ogee configuration, similar to the case, and ornamented with the bead-work *c* and scroll and leaflet ornaments *d*, as represented.

I claim as my invention—

1. The design of the lock-case with the ornamental configuration of a locomotive-engine, as represented.
2. The design of the bead-work, and scroll ornaments, and leaflets upon the lock-case or nosing, as represented.

Signed by me this 29th day of November, 1873.

LOUIS WIDMAYER.
